SPARK INTENSIFIER

Filed May 12, 1931

UNITED STATES PATENT OFFICE

FREDERIC L. DOERRHOFER, OF MAPLEWOOD, NEW JERSEY, ASSIGNOR OF ONE-HALF
TO HERBERT REDMAN

SPARK INTENSIFIER

Application filed May 12, 1931. Serial No. 536,901.

My present invention has reference to improvements in the ignition system of internal combustion engines and has for its primary object the provision of means interposed between the spark point and the distributor of an ignition system for stepping up the current until it reaches its maximum firing value for distribution to the spark plugs.

10 A further object is the provision of a spark intensifier which is arranged between the coil and the distributor so that only a single intensifier is required irrespective of the number of cylinders of the engine and wherein the 15 current is stepped up before the distributor is reached.

A further object is the provision of a spark intensifier that is characterized by simplicity in construction, and reliability and efficiency 20 in practical use.

To the attainment of the foregoing the invention consists in the improvement herein-after described and definitely claimed.

In the drawing:

25 Figure 1 is an elevation illustrating the invention connected to the distributor of the ignition system of an internal combustion engine.

Figure 2 is a central longitudinal sectional view through the improvement.

Figure 3 is a transverse sectional view approximately on the line 3—3 of Figure 2.

Figure 4 is a similar sectional view approximately on the line 4—4 of Figure 2.

35 Figure 5 is a perspective view of the socket and the flanged discs that provide the compartments of the intensifier.

Figure 6 is a similar view of the plug.

Figure 7 is a plan view of a blank from 40 which the socket is formed.

Figure 8 is a similar view of a blank from which the plug is formed.

In the drawing the numeral 10 indicates a distributor of any well known type employed for conducting the current in timed relation to the spark plugs from the spark coil of the ignition system of an automobile or other gasoline motor. The conductor wire that leads from the spark coil to the distributor is indicated by the numeral 11. In

carrying out my invention this main ignition wire 11 is removed from the distributor and has its end received in the socket of my improved spark intensifier. The intensifier comprises a body portion which is in the 55 nature of a sleeve 12 of insulating material. In the outer end of the sleeve I arrange the metal socket of the improvement. As disclosed by Figure 7 of the drawing the socket is made up from a single piece of metal which 60 is cross-shaped in plan which has its central or body portion, at the juncture of the right angular arms thereof, formed with slots 13 whose inner or terminal walls are rounded. The body is provided with curved score lines 65 14, which are arranged in a line with the inner walls of the notches 13 and with said walls afford a complete surface. The arms 14 are bent angularly in the same direction upon the score lines 14 and are arched transversely upon themselves to provide a tubular socket, the arms 15 of which exert a sufficient spring tension away from each other as to frictionally engage with the bore of the insulator sleeve 12, and the V-shaped slots 70 13 provide notches between the arms. The tubular sleeve, when in assembled position thus presents a cross sectionally round body portion and a flat bottom portion. The complete sleeve is indicated in the drawing by 75 the numeral 16. Preferably the sleeve is constructed from a strip of silver that I have found to be of high electric conductivity. As a matter-of-fact, all of the parts of my intensifier except the sleeve 12 are like- 80 wise of silver.

In the second end of the sleeve 12 there is received the upper widened end 17 of a plug 18 that is designed to be received in the central socket or opening in the distributor 90 10 in which the main ignition wire 11 is normally received. The socket 18 is also constructed from a cross-shaped strip of metal, as disclosed by Figure 8, and the right angularly arranged arms, at the juncture with the body thereof, are formed with V-shaped notches 20, the outer ends of the said arms being widened laterally, as at 21. The arms are bent on rounded score lines from the bottom or body at the same direction and are 100

arched in cross section, as are the ends 21, and these ends 21 have their edges in contacting engagement and provide the widened and opened end 17 of the plug 18 that is disclosed by Figures 2 and 6 of the drawing. The widened and open end of the plug is offset from the remainder thereof so that the body of the plug is reduced and the widened end 17 thereof will frictionally contact with the bore of the sleeve 12 and thereby effectively hold the plug in the sleeve.

Arranged in the bore of the sleeve 12, resting on the upper end 17 of the plug 18 and having its body 22 in frictional contact with the bore of the sleeve 12 there is a cup-shaped member 23 and in this cup there rests metal balls 24. The cup 23 rests on the end of the plug 18 in the sleeve 12. Directly above but spaced from the cup 23 and the balls 24 therein there is an inverted cup 25 and resting upon the inverted cup 25 there is another and shallower cup 26. The cup 26 provides a receptacle for metal spheres 28. Above the cup 26 and the spheres therein there is another inverted cup 29. The facing pairs of cups provide therebetween short circuiting pockets or compartments for the current that is directed through the intensifier. The principle of the intensifier is similar to those of other devices for the same purpose. The electric current directed through the wire 11 meets an obstruction in both of the compartments or chambers 30 and 31 between the casting cups. These breaks in the current disturb its equilibrium, causing the same to back up voltage to jump over the obstructions in proportion to the degree of its disturbed equilibrium and the voltage or force erected by the electricity to resume its balance will, when the break or obstruction is passed create a spark from which intense heat is emitted. The spheres 24 and 28 are important elements in my construction, as the spheres create several points from which the currents must jump. Current leaving the coil will, of course, flow through the conductor 11, through the intensifier and is stepped up in its passage from the electrodes provided by the cups and spheres and an increased amount of current will pass from the distributor to each of the spark plugs.

The invention is susceptible to various changes in its form, proportions and minor details of construction and the right is herein reserved to make such changes therefrom as fairly fall within the scope of what I claim.

Having described the invention, I claim:

1. A spark intensifier for the high tension conductor of the distributor in the ignition system of an internal combustion engine, comprising a sleeve of insulating material, a split metal resilient socket in one end of the sleeve exerting a frictional engagement thereagainst and designed to receive the conductor wire therein, a split metal resilient

plug in and frictionally engaging with the bore in the second end of the sleeve and extending therebeyond, and said plug designed to be received in the socket of the distributor, oppositely directed metal cups arranged in pairs in the sleeve between the socket and the plug and the open confronting ends of the cups being spaced from each other, and pyramidal arranged spheres of high electric conductivity loosely received in the respective pairs of cups.

2. A spark intensifier for the purpose set forth, comprising a sleeve of insulating material, a metal socket in one end of the sleeve for the reception of a conductor wire, said socket having its body slotted to provide spring elements which exert a friction engagement with the bore of the sleeve and the said body of the socket being provided with openings in a line with the inner wall thereof, a metal plug of tubular formation and having its widened and opened end received in the second end of the sleeve, said plug having its body slotted to afford individual friction elements to contact with the bore of the sleeve, and the outer end of the sleeve designed to be received in the socket of a distributor, metal cups in the sleeve, and the outer cups being in contact respectively with the socket and with the plug, said cups being arranged in pairs that have their open mouths confronting but spaced from each other, and pyramidal arranged spheres of high electric conductivity freely arranged in each of the pairs of cups.

In testimony whereof I affix my signature.

FREDERIC L. DOERRHOFER.
